GAMING DEVICE

Olav T. Bergenn, Brooklyn, N. Y.

Application July 19, 1938, Serial No. 219,952

3 Claims. (Cl. 273—97)

This invention relates to gaming devices and the like.

Among the objects of the present invention, it is aimed to provide an improved cup and ball gaming device consisting essentially of a handle having a suction cup attached thereto and a ball connected to the handle by a string such as an elastic string, the game having for an object the capture of the ball by the suction cup.

These and other features, capabilities and advantages of the invention will appear from the subjoined detail description of one specific embodiment thereof illustrated in the accompanying drawing in which

Fig. 1 is a side elevation partly in section of the gaming device with the ball gripped by the suction cup;

Fig. 2 is a side elevation of the device with the suction cup removed;

Fig. 3 is a plan view of the handle shown in Fig. 2 with the suction cup removed;

Fig. 4 is a side elevation of the suction cup removed from the handle; and

Fig. 5 is a plan view of the suction cup looking at the lower end thereof.

In the embodiment shown, there is provided a handle 1 composed of wood or the like with a projection 2 at one end thereof having a diminished neck 3. The projection 2 is provided to anchor the suction cup 4 in place as illustrated in Fig. 1, which suction cup 4 has a cylindrical recess 5 normally of less diameter than the diameter of the outer portion of the projection 2 so that the neck portion 6 of the cup 4 may firmly grip the projection 2 and anchor the same in place as indicated in Fig. 1. Beyond the neck portion 6, the suction cup 4 has a dished suction shell portion 7.

To the side of the handle 1, there is connected a string such as the rubber band 8 by means of a tack 9 or the like, which rubber band 8 is connected at its end to a ball 10 preferably by extending an end of the band 8 doubled upon itself into a slit cut into the ball 10.

With the proportions illustrated in the drawings and the composition specified, it has been found that excellent results are achieved with this gaming device when the handle 1 is composed of wood or the like of about eight inches in length by about one inch in diameter; the shell portion 7 of the suction cup composed of gum rubber has a wall of about three thirty-seconds

of an inch thick with its free end having an outer diameter before flexure of about fifteen-sixteenths of an inch as shown in Fig. 4 and with its free end having an outer diameter after flexure as shown in Fig. 1 of close to one and two-sixteenths of an inch; the rubber band 8 about eighteen inches in length, one-eighth inch in width and about one thirty-second of an inch in thickness; and the ball 10 composed of sponge rubber of about two inches in diameter, weighing about two ounces and having a smooth glossy surface finish formed by a coating of "Nu-Enamel" as an instance.

Obviously the proportions illustrated and compositions specified may be varied without departing from the spirit of the invention. As an instance, with a smaller ball either a smaller suction cup may be used or a suction cup having a concavity of greater depth.

In the use of this gaming device as is well known with this type of ball and cup toy, it is of course obvious that the user will grip the handle 1 and throw the ball 10 into the air against the tension of the rubber band 8 and try to retrieve the ball 10 into the position shown in Fig. 1 by the suction cup 4.

It is obvious that various changes and modifications may be made to the details of construction without departing from the general spirit of the invention as set forth in the appended claims.

I claim:

1. The combination of a handle, a suction cup secured to said handle, a smooth surfaced ball, and a string connecting said ball to said handle.

2. The combination of a handle, a gum rubber suction cup secured to one end of said handle with its suction cup portion facing outwardly therefrom, a sponge rubber ball having a glossy surface finish, and a rubber band connecting said ball to said handle.

3. The combination of a wooden handle having a projection at one end thereof, a gum rubber suction cup secured to said projection with its suction cup facing outwardly, a sponge rubber ball about two inches in diameter, weighing about two ounces and having a smooth glossy finish, and a rubber band about eighteen inches in length, one-eighth of an inch in width and one thirty-second of an inch in thickness connecting said ball to said handle.

OLAV T. BERGENN.
